COMBINATION LOCATING-AND-MARKING GAUGE FOR JUNCTION BOXES

Herschel L. Sunley, 1814 S. 8th St., Springfield, Ill.

Filed Oct. 7, 1965, Ser. No. 87,363

Term of patent 14 years

(Cl. D52—6)

FIGURE 1 is a top plan view of a combination locating-and-marking gauge for junction boxes, showing my new design;

FIGURE 2 is a bottom plan view of FIGURE 1;

FIGURE 3 is an end elevational view looking at the lower end of FIGURE 1; and

FIGURE 4 is a perspective view looking beneath the lower right hand corner of FIGURE 1.

Portions of the elongated measuring bars of the gauge are broken away for convenience of illustration only.

I claim:

The ornamental design for a combination locating-and-marking gauge for junction boxes, as shown and described.
